United States Patent Office

Des. 180,053
Patented Apr. 9, 1957

180,053

COLLAPSIBLE DISPLAY ORNAMENT OR SIMILAR ARTICLE

Joseph Zalewski, Cambridge, Mass., assignor to Austen
Display Inc., New York, N. Y., a corporation of New York

Application February 21, 1956, Serial No. 40,244

Term of patent 7 years

(Cl. D29—1)

Fig. 1

Fig. 2

Fig. 3

Fig. 1 is a perspective view of a collapsible display ornament or a similar article, showing my new design illustrated in expanded position;

Fig. 2 is an end elevational view thereof, but in collapsed position; and

Fig. 3 is a top plan view of the collapsed article of Fig. 2.

I claim:

The ornamental design for a collapsible display ornament or a similar article, substantially as shown.
